United States Patent Office.

GEORGE F. BISSELL, OF ONEONTA, NEW YORK.

Letters Patent No. 96,771, dated November 16, 1869.

IMPROVEMENT IN FARM-GATES.

The Schedule referred to in these Letters Patent and making part of the same.

To all whom it may concern:

Be it known that I, GEORGE F. BISSELL, of Oneonta, in the county of Otsego, and State of New York, have invented a new and improved Farm-Gate; and I do hereby declare that the following is a full, clear, and exact description thereof, which will enable others skilled in the art to make and use the same, reference being had to the accompanying drawings, forming part of this specification.

My object in this invention is to improve and perfect the farm-gate, various styles of which are in use; and

The invention consists in the method of operating and supporting the same, as hereinafter more fully described.

In the accompanying drawing—

Figure 1 represents a side elevation of a gate, operated according to my invention.

Figure 2 is a top view, with the rail broken away, showing the gate open.

Similar letters of reference indicate corresponding parts.

This gate is made in the ordinary manner of horizontal rails and vertical slats, supported by means of gate-posts at each end, as is usual.

A is the gate, and

B B' represent the gate-posts.

The gate is supported, on its back end, on a revolving pulley, E, which is attached to one portion of a hinge. The other portion of the hinge is securely fastened to the post B.

C is the portion of the hinge which is screwed or fastened to the post B.

D is the portion which bears the pulley E.

Attached to the upper portion of the post D are horns F F', against which the rail of the gate rests.

These horns not only serve to keep the gate on a line with the face of the suspending-pulley E when the gate is opened, but the inner horn catches into the staple G when the gate is shoved back for opening, as seen in fig. 2.

The hinge is formed by eyes I on the part C, and

hooks H H on the part D, and it will be seen that the eyes are so formed that when the gate is opened, as seen in fig. 2, the hooks will drop down into the recess or cavities seen in fig. 1, and thereby hold the gate open, as seen in fig. 2.

In closing the gate, the hooks slide up the inclined planes, and resume the position seen in fig. 1, when the gate is again closed.

J represents a hook for confining the lower portion or bottom of the gate, inserted diagonally into the part B, with the shoulder bevelled on each side, as seen at k, so as to give a flat surface bearing against the gate-rail, both when the gate is open and when it is closed.

L is a fastening-hook confined by a pivot in the front end of the gate, and forms a self-fastening catch when the gate is closed.

The gate rests in the groove of the pulley loosely, and may be detached entirely from the hinge and the posts with the greatest ease, or raised, so that the second rail will rest in the pulley in case of a deep snow, another hole in the post being provided for the hook J, and another staple, G, being placed in that rail, for receiving the horn E.

Having thus fully described my invention,

What I claim as new, and desire to secure by Letters Patent, is—

1. The combination of staples G on the rails, with horns F, arranged on the post B, in the manner described.

2. The combination of staples G, arranged on that side of the centre nearest to the front thereof, and the horns F with the hinge and post, said parts co-operating to swing the gate at right angles to its ordinary direction.

The above specification of my invention signed by me, this 19th day of August, 1869.

GEORGE F. BISSELL.
